(57) **CLAIM**

The ornamental design for a heater module, as shown and described.

DESCRIPTION

FIG. 1 is a top, front perspective view of an embodiment of a heater module;

FIG. 2 is a top, rear perspective view from the right side thereof;

FIG. 3 is a top, rear perspective view from the left side thereof;

FIG. 4 is a front, elevational view thereof;

FIG. 5 is a rear, elevational view thereof;

FIG. 6 is a top plan view thereof;

FIG. 7 is a bottom plan view thereof;

FIG. 8 is a left-side, elevational view thereof; and,

FIG. 9 is a right-side, elevational view thereof.

The broken lines shown in the drawings illustrate portions of the heater module that form no part of the claim.
